UNITED STATES PATENT OFFICE.

CHARLES WITTE AND HENRY M. LUICK, OF NEW YORK, N. Y.

BICYCLE-BRAKE.

SPECIFICATION forming part of Letters Patent No. 634,421, dated October 3, 1899.

Application filed July 12, 1899. Serial No. 723,534. (No model.)

To all whom it may concern:

Be it known that we, CHARLES WITTE, a citizen of Germany, and HENRY M. LUICK, a citizen of the United States, residing at New York city, New York, have invented certain new and useful Improvements in Cycle-Brakes, of which the following is a specification.

This invention relates to a cycle-brake of novel construction in which the brake-shoe acts against a disk fitted upon the crank-shaft, so that the rubber tires are not injured by the application of the brake.

The invention consists in the various features of construction, fully pointed out in the claim.

In the accompanying drawings, Figure 1 is a side elevation of the brake; Fig. 2, a rear view of the same; Fig. 3, a plan; Fig. 4, a section on line 4-4, Fig. 3; and Fig. 5, a detail of the brake-lever.

The letter *a* represents the crank-axle of the cycle, upon one end of which is mounted the usual sprocket-wheel, while a brake-disk *b* is mounted upon the opposite end. The disk *b* is engaged by the brake-shoe *c*, which at its upper and lower ends is guided within the grooved rails of a frame *d*, attached to the crank-hanger *a'* of axle *a* at *d'*. The front of the frame *d* is perforated and forms the guide for a mortised slide *e*, that encompasses a strong spring *f*, the rear end of which is secured to the brake-shoe *c*. To the forward end of slide *e* is pivoted a lever *g*, fulcrumed 35 at *g'* to a collar *h*, clamped to the frame-bar

i. A brake-chain *j*, running around pulley *j'*, connects lever *g* to the brake-lever *k*, pivoted to a clasp *k'*, that surrounds the handle-bar *l*. One or more weak retracting-springs *m* connect the brake-shoe *c* with the front of frame *d*.

When the brake-lever *k* is raised partly, the lever *g* will be tilted to move the slide *e* inwardly and apply the brake-shoe to the disk *b* without compressing strong spring *f*. When a "full brake" is desired, the lever *k* is raised fully to compress the spring *f* and apply the shoe with additional power. Thus it will be seen that the rider can freely control the force with which the brake is applied. Upon a release of the brake-lever the weak springs *m* will throw the brake-shoe off and restore the parts to their normal position.

What we claim is—

In a cycle-brake, the combination of a crank-shaft with a disk mounted thereon, a fixed frame, a brake-shoe guided thereby, a slide engaging the frame, a strong spring that connects the slide to the shoe, a lever pivoted to the slide, a brake-chain for actuating the lever, and a weak retracting-spring, substantially as specified.

Signed by us, at New York city, New York, this 11th day of July, 1899.

CHARLES WITTE.
HENRY M. LUICK.
